Primary Examiner — Susan Moon Lee(74) *Attorney, Agent, or Firm* — Law Offices of Alozie Etufugh, PLLC(57) **CLAIM**

We claim the ornamental design for a pet feeder apparatus, as shown and described.

DESCRIPTION

FIG. 1 is an exploded top perspective view of a pet feeder apparatus in accordance with our new design;

FIG. 2 is an exploded bottom perspective view thereof;

FIG. 3 is a top plan view thereof;

FIG. 4 is a bottom view thereof;

FIG. 5 is a right side elevation view of the pet feeder apparatus in explosion, the left side elevation being a mirror image thereof;

FIG. 6 is a front elevation view thereof;

FIG. 7 is a rear elevation view thereof;

FIG. 8 is an assembled top perspective view of the pet feeder apparatus;

FIG. 9 is a bottom perspective view thereof;

FIG. 10 is a top plan view thereof;

FIG. 11 is a bottom view thereof;

FIG. 12 is a right side elevation view of the assembled pet feeder apparatus, the left side elevation being a mirror image thereof;

FIG. 13 is a front elevation view thereof; and,

FIG. 14 is a rear elevation view thereof.
